WALLPAPER REMOVER

Ethan A. Schaeffer, Jr., Springfield, Ohio

Application February 25, 1935, Serial No. 7,998

6 Claims. (Cl. 216—8)

This invention relates to improvements in a wall paper remover of the type in which a steam pan is employed for preliminarily moistening and softening the paper preparatory to removal, the invention particularly relating to the steam jet used in a device of this character.

An object of the present invention is to provide an improved jet for a device of the character described which will utilize the advantages offered by the use of high pressure steam.

In the steam pan shown in the accompanying drawing, the loosening effect is first improved by a corrected location of the jet, and further improved by the manner in which the jet is formed to take full advantage of the proper location as corrected; still further, the jet is improved to utilize to the fullest extent the opportunity to employ steam of much higher pressure than was heretofore available. The boilers furnishing the steam for this work are small, portable boilers of a capacity of not much more than two gallons of water, and in the older boilers, which were fired by a liquid fuel such as gasoline, the pressure was limited to thirty pounds per square inch because of the two hazards of pressure and more or less open flame. In the newer boilers for which the present pan and its improved jet were especially designed, a pressure of approximately ninety pounds per square inch is permitted due to the elimination of the hazard of fire, as the new boilers are electrically heated.

No great amount of dependence is placed on the high pressure steam for mere saturation, since saturation is only the natural penetration of the fibres of the paper by the hot water of condensation and the action is not speeded up to any great extent by pressure. The great advantage afforded by the combination of the improved jet in the corrected location coupled with the use of the high pressure steam is found in the removal of an accumulation of several thicknesses of paper such as is often met with in rooms that have been repapered many times. With the improved jet, a portion of the steam is caused to impinge directly on the paper at the high velocity brought about by the high pressure whereby a puncture is made through the several layers, the steam flowing through the puncture and expanding between the wall and the adjacent paper to form a "blister". In the meantime, other orifices of the improved jet are directing steam to a plurality of points on the surface of the paper adjacent the edges or periphery of the blister to thereby prepare the surface for a succeeding puncture on another positioning of the pan.

It can be seen that, compared with the old method, the operation of loosening an accumulation of paper as described is almost as many times faster by the use of high pressure steam as there are layers of paper, since there is in reality but one layer of paste holding the accumulation to the wall, and this paste layer is the one which receives the effect of the puncturing flow of steam. The labor of scraping is also reduced to a minimum, as very often the accumulated paper falls from the wall by its own weight.

In the accompanying drawing:

Fig. 1 is a perspective rear view of a steam pan having an improved jet at the corrected location in the pan.

Fig. 2 is a fragmentary enlarged elevation of the pan, looking toward the open side which is placed against the wall.

Fig. 3 is a view partly in side elevation and partly in vertical section, the sectional portion being taken on the line 3—3 of Fig. 2.

Fig. 4 is a fragmentary enlarged section on the line 4—4 of Fig. 2, showing in detail the construction of the improved jet.

Fig. 5 is a fragmentary view, a portion of which is partly in elevation and partly in section similar to Fig. 4, showing a supplemental jet used in connection with the improved jet.

Referring to the drawing, the improved jet is indicated in general at 1, and as can be seen in Figs. 1, 2 and 3, is positioned in the approximate central portion of the shallow pan 2 which otherwise follows a well known construction, in that it is closed by the rear end 11 and the sides 15 but is open at its forward end. The jet 1 is formed of hexagon bar stock, and a portion of its length is left in the original dimensions whereby a base 3 is provided on which a wrench may be placed. Extending axially from the base 3 is a reduced diameter cylindrical extension 4 which is exteriorly threaded at its extremity for a purpose which appears later.

The orifice which provides the puncturing flow is indicated at 5 (Figs. 4 and 5). This orifice is a comparatively small bore at the end of the extension 4 and is axially arranged with respect to the bore in the jet 1, and its diameter, and those of other orifices which will be described, are computed with the idea of steam conservation, and, especially referring to the orifice 5, that the desired velocity will be attained. Steam is fed to the orifice 5 from an enlarged diameter feeding bore 6, and to the bore 6 from the larger interiorly threaded bore 7, into which is threaded the forward end 8' of the curved conduit 8 threaded at 55

its outer end into the valve 9, the support for the valve being effected by the clamping effect of the jet 1 and a jam nut 10 also threaded on the end 8' of the conduit 8 which passes through a central opening in the rear end 11 of the pan 2.

The valve 9 is of ordinary construction and is automatically opened when the operator places the open end of the pan against the wall, there 10 being provided a pin 12 which projects laterally from the valve handle 13 and extending through an elongated opening 14 in the end 11 of the pan beyond the wall contacting sides 15 of the pan. When the pan is removed from the wall, the valve 15 proper 9' is closed by a spring 9" and when the pan is placed against the wall, the rearward movement of the pin 12 opens the valve. A flexible hose 17 carries steam under pressure to the valve from a boiler (not shown).

20 It will be noticed that the orifice 5 is short, and as is well known, a restriction to a flow, if suitably short, does not impede the flow or reduce the volume of flow, and does increase the velocity. By design, this high velocity effect is retained 25 as much as possible, and since the end of the jet is within, say, one-quarter inch of the paper, and since there is some softening of the paper due to condensation at the region where the puncturing flow, represented at 5', Fig. 4, by 30 dash lines, is impinging on the paper, the high pressure easily makes the small perforation needed, and the steam following forces the paper from the wall to form the "blister" previously mentioned.

35 In order to bring about a surface saturation in addition to puncturing the paper, other orifices are provided which also communicate with the feeding bore 6. In the present case, four such surface saturating orifices indicated at 18 40 are provided, and the diameter of the orifices 18 is restricted so that ample penetrating power will be retained in the puncturing flow issuing 45 from the orifice 5. These orifices 18 are radially disposed when viewed in one plane, and the jet is so placed as seen in Fig. 2 that the flows issuing therefrom reach the far corners of the pan. In another plane as shown in Figs. 4 and 5, the orifices 18 stand at a slight angle with the axis 50 of the jet so that the flows strike the surface of the paper, it being clear that due to the angle of the flows as shown by the long dash lines 19, that such will be the case. The reference character 19 is also used in Fig. 2 to indicate the direction of the saturating flows from the orifices 18. 55 Thus it is seen that the major portion of this steam condenses on the paper, rather than on the pan surfaces.

The diameter of each of the orifices described is also held to as low a dimension as is consistent 60 with the work to be done to prevent a too rapid exhaustion of the necessarily small boiler, and also, especially referring to the puncturing orifice 5, to provide penetration, it being clear that with 65 too large orifices, the boiler would soon be exhausted of steam or at least the pressure would be unduly lowered, and in all of these conditions, the puncturing effect of the orifice 5 would be reduced, if not lost entirely. The surface saturating orifices 18 are useful in softening paper 70 when there are but one or two thicknesses on the wall, and also in preparing the outer surface for puncturing when there is the accumulation of many layers as was previously mentioned, since in use the operator moves the pan from place to 75 place on the wall.

For use in softening paper behind radiators, an accessory is employed which is in the nature of an extended tube to bring a jet adjacent the paper. This member is shown in Fig. 5, and is a tube 20 having secured at one end a coupling 21, 8 and in the present case, a single orifice jet 22, secured at its other end. In use, this member is threaded on the exterior thread on the cylindrical extension 4 of the jet 1, and being made sufficiently long, the operator is able to reach the 10 paper to the rear of the radiator by inserting the tube between the radiator sections, controlling the flow of steam by manually opening and closing of the valve. Since there is no need of steam from the surface saturating orifices 18 of the jet 15 1 at this time, these orifices are closed by the coupling 21 being screwed down over them, all the steam then being used flowing from the small orifice 23 in the extension jet 22.

It can then be seen that in the present invention 20 advantage is taken of placing the jet in the center of the pan whereby the side or surface saturating orifices are approximately equally spaced from the edges or corners of the pan, and that flows from such orifices are of approximate 25 equal length; that by providing that the surface saturating orifices are at the slight angle noted with relation to the longitudinal axis of the jet that the steam is directed to the paper where the saturation due to condensation is effective 30 to soften the paper, which is not true of the steam that condenses on the pan; and the labor of removing the heavy accumulations of paper is reduced by the perforating effect of the main orifice.

The lower side of the pan has a trough 24 to 35 receive the water condensed from the steam, and an operator's handle 25 on a tubular member 26 which is connected to the rear end of the pan furnishes the means for manipulating the device; this tubular member being further connected to the pan by the strap 27.

Having thus described my invention, I claim:

1. In a wall paper remover, the combination of a pan open at one end, a steam jet carried by said pan and having an axially arranged orifice 45 and a plurality of lateral orifices, and a connection for supplying steam under pressure to said jet

2. In a wall paper remover, the combination of a pan open at one end, a steam jet centrally 50 positioned on the closed end of said pan and having an axially-arranged orifice and a plurality of lateral orifices, and a connection for supplying steam under pressure to said jet.

3. In a wall paper remover, the combination 55 of a pan having one rear end member and four straight sides, said pan being open at its forward end, a steam jet carried by said pan having an axially-arranged orifice and a plurality of lateral orifices, said lateral orifices being arranged 60 to direct steam toward the corners of said pan, and a connection for supplying steam under pressure to said jet.

4. In a wall paper remover, the combination of a pan open at one end, a steam jet, a connection for supplying steam to said jet extending through the closed end of said pan, said jet being threaded upon said connection and located in said pan so as to be readily removable from said pan, said jet having an axially arranged orifice, 70 and a plurality of lateral orifices.

5. In a wall paper remover, the combination of a pan open at one end, a steam jet carried by said pan and having an axially arranged orifice and a plurality of lateral orifices, a connection for 75

supplying steam under pressure to said jet, said jet having exterior screw threads, and an auxiliary tube adapted to have one end screwed upon said nipple so as to close said lateral orifices, said tube having an orifice at the other end thereof.

5. In a wall paper remover, the combination of a pan having one rear end member and four straight sides, said pan being open at its forward

end, a steam jet carried by said pan having an axially-arranged orifice and a plurality of lateral orifices, said lateral orifices being arranged to direct steam toward the corners of said pan, and a connection for supplying steam under pressure to said jet, said lateral orifices being arranged to direct steam toward the open end of the pan.
